UNITED STATES PATENT OFFICE.

WILHELM E. DÖRR, OF UBERLINGEN, GERMANY, ASSIGNOR TO LUFTSCHIFFBAU ZEPPELIN GESELLSCHAFT MIT BESCHRÄNKTER HAFTUNG, OF FRIEDRICHSHAFEN, GERMANY.

GAS-INFLATED AIRSHIP.

Application filed July 1, 1927, Serial No. 202,852, and in Germany July 15, 1926.

My invention relates to gas inflated airships and has special reference to airships of this kind in which two different kinds of gases are used.

5 The hull of airships generally is subdivided into compartments. Into these compartments gas cells are inserted. Usually in rigid airships there are transverse members called rings having circumferential 10 girders stayed by an internal wire bracing. This wire bracing subdivides the inner hollow space of the hull into the above mentioned compartments.

Recently it has been suggested that the 15 structure of the transverse members be altered. Instead of providing relatively small circumferential ring girders stayed by the wire bracing, ring girders of a considerable height or cross section are suggested to 20 be used so that the inner bracing can be dispensed with. The gas cells which formerly were supported against the wire bracing of a ring, now bear only one against the other with their end walls. These end walls consequently must be constructed of a relatively 25 great amount of normally slack material; that is, more material is employed progressively toward the central portion of the end wall than that which would be required to 30 construct an end wall normally conforming to a transverse plane of the gas cell, so that such walls may bulge into the adjacent compartment in the event one of the gas cells should be deflated. For the purpose of 35 limiting the extent of such bulging into adjacent compartments a loose net-work of cords or the like may be provided. This net-work has its edges fastened to the greater circumferential ring structure and its capacity 40 for bulging is sufficiently great to allow for a considerable pitch in the bulging of the end wall of a gas cell. All this will be understood better when later referring to the drawing.

45 According to my invention, the gas cells are provided with double end walls composed of a relatively great amount of normally slack material, and the space between these two end walls is utilized by inflating 50 it with one kind of gas, whereas the main portion of the gas cell is inflated with the other kind of gas. Accordingly this gas space between the double end walls is situated when inflated partly in one of the com-

partments and partly in the compartment 55 adjacent thereto, the median plane of the transverse ring being approximately coincident with the median plane of the new gas space.

5 The double end walls of a gas cell may of 60 course be provided at both ends of a cell, but I prefer to have it only at one end thereof.

65 My invention is of special importance in conjunction with airships the motors of 65 which are fed with gaseous fuel according to the latest improvements. In such airships the gas space between the double end walls according to my invention should be 70 inflated with the fuel gas, whereas the main gas space of the gas cell is reserved for the lifting gas. With this arrangement the fuel gas will always be under a certain pressure resulting from the pressure exerted by adjacent lifting gas, and it will thus be forced 75 through the pipes or conducts to the engine or engines of the airship. As the fuel gas is consumed, the adjacent double end walls will approach each other, beginning 80 with their upper portions, and thereby the lower level of the lifting gas will move upwardly.

Having given a general description of my 85 invention I now want to point it out more in detail referring to the drawings which represent an example embodying my invention.

90 The figure represents a fragmentary longitudinal vertical section through the hull of a rigid airship.

95 The outer portion of the hull is designated by the numeral 1. Transversely disposed rigid frames 2 are in the form of rings composed of girders with a relatively large cross section, requiring no wire bracing, whereas rings 3 are the well-known wire braced cross members. Three gas cells 4, 4' and 4'' are shown. One end wall of each of these cells is double as shown at 8 and 9, whereas the other end wall of each cell is single as indicated at 10. The gas cells 4, 4' and 4'' are 100 inflated with lifting gas, for example hydrogen or helium, whereas the spaces 5 and 5' between the double end walls, 8 and 9 are inflated with the fuel gas. There are openings 11 in the walls of the fuel gas space, opening into conduits 12, by which the fuel gas is conducted to the engine 13 in the 105

motor car 14. The lifting gas space has valves 15 opening into gas ducts 16 by which the gas is led to openings 17 in the outer cover 1. The fuel gas spaces also have valves 18 by which fuel gas may escape in case of emergency.

I do not want to be limited to the details described or shown in the drawings, as many variations occur to those skilled in the art.

10. What I claim is:

1. A rigid airship comprising a hull; a transverse member in said hull, said member forming a circumferential ring with an open inner space; gas cells in said hull, two of said gas cells meeting and bearing against each other with one of their two end walls, respectively, substantially in the transverse plane where said transverse member is situated; one of said end walls of said cells being double, the space between said double

end walls being adapted to be inflated with gas also.

2. A gas cell of substantially cylindrical shape, adapted to be inserted into the hull of a rigid airship, one end wall of said cell composed of a relatively great amount of normally slack material and being double, the space between said double end walls when inflated forming a gas space of lentil-like shape.

3. A gas cell of substantially cylindrical shape inserted into the hull of a rigid airship, one end wall of said cell composed of a relatively great amount of normally slack material and being double, the space between said double end walls being inflated with a gaseous fuel for the motor of said airship, the main space of said gas cell being inflated with lifting gas.

WILHELM E. DÖRR.
